Primary Examiner — Eliza Z Bennett-Hattan(74) *Attorney, Agent, or Firm* — Merchant & Gould P.C.(57) **CLAIM**

The ornamental design for a nasal airway medical instrument, as shown and described.

DESCRIPTION

FIG. 1 is a perspective view of the nasal airway medical instrument.

FIG. 2 is a right side view thereof.

FIG. 3 is a left side view thereof.

FIG. 4 is a rear view thereof.

FIG. 5 is a front view thereof.

FIG. 6 is a top view thereof; and,

FIG. 7 is a bottom view thereof.

The broken lines represent portions of the nasal airway medical instrument that form no part of the claimed design.
